(57) **CLAIM**

The ornamental design for a pen tray, as shown and described.

DESCRIPTION

FIG. 1 is a perspective view of a first embodiment of a pen tray in accordance with my design;

FIG. 2 is a top view;

FIG. 3 is a bottom view;

FIG. 4 is a side view; the opposite view being a mirror image thereof;

FIG. 5 is a front view; the opposite view being a mirror image thereof;

FIG. 6 is an exploded perspective view with a folded I-card;

FIG. 7 is a perspective view of a second embodiment of a pen tray in accordance with my design;

FIG. 8 is a top view;

FIG. 9 is a bottom view;

FIG. 10 is a side view; the opposite view being a mirror image thereof;

FIG. 11 is a front view; the opposite view being a mirror image thereof;

FIG. 12 is an exploded perspective view;

FIG. 13 is a perspective view of a third embodiment of a pen tray in accordance with my design;

FIG. 14 is a top view;

FIG. 15 is a bottom view;

FIG. 16 is a side view; the opposite view being a mirror image thereof;

FIG. 17 is a front view; the opposite view being a mirror image thereof;

FIG. 18 is an exploded perspective view;

FIG. 19 is a perspective view of a fourth embodiment of a pen tray in accordance with my design;

FIG. 20 is a top view;

FIG. 21 is a bottom view;

FIG. 22 is a side view; the opposite view being a mirror image thereof;

FIG. 23 is a front view; the opposite view being a mirror image thereof; and,

FIG. 24 is an exploded perspective view.

The broken lines in FIGS. 3, 9, 15 and 21 are included for the purpose of illustrating the bottom surface that forms no part of the claimed design.

The stippling is understood to be distributed uniformly over the surfaces on which it is partially shown; it represents a surface texture and forms a part of the claimed design.
